UNITED STATES PATENT OFFICE.

WILLIAM C. McCOY, OF CLEVELAND, OHIO, ASSIGNOR TO THE CLEVELAND TRUST COMPANY, OF CLEVELAND, OHIO, A CORPORATION OF OHIO.

ELECTRICAL INDICATING INSTRUMENT.

Application filed June 30, 1927. Serial No. 202,479.

This invention relates to electrical indicating instruments and particularly to an electrically operated instrument for indicating conditions existing at a remote point.

5 One of the objects of the present invention is to provide an electrical indicating instrument that shall be substantially free from errors due to residual magnetism, that shall be inexpensive to manufacture, and that shall 10 be of rugged construction and reliable in its operation.

An additional object of the invention is to provide an instrument of the above character having a relatively light weight armature 15 vane that constitutes a damping vane for the instrument.

A further object of the invention is to provide an improved instrument structure of inexpensive character that shall readily accommodate the mounting thereon of different forms of casings, particularly for mounting 20 in instrument panels of automotive vehicles.

An additional object of the invention is to provide an armature carrying vane to which the indicator arm is directly secured and from 25 which the indicator arm receives its position.

A further object of the invention is to connect the base of the instrument with the dial supporting face solely by the core 4 of the 30 actuating coils.

An additional object of the invention is to provide an improved pivotal support for an armature of the character herein proposed.

Figure 1 of the accompanying drawing is 35 a front or face view of an instrument embodying the invention.

Fig. 2 is a sectional view of the instrument taken substantially on the line 2—2 of Fig. 1.

Fig. 3 is a cross sectional view of the instrument shown in Fig. 1 taken substantially 40 on line 3—3 thereof.

Fig. 4 is a sectional view, taken substantially on line 4—4 of Fig. 3, of the magnetic parts of the instrument with the energizing coil 45 moved.

Fig. 5 is a view in perspective of the armature assembly of the instrument.

Fig. 6 is a diagrammatic view of a control system for use in connection with the instrument.

Fig. 7 is a face view of a modified form of instrument constructed in accordance with the invention.

Fig. 8 is a side elevational view, taken substantially on line 8—8 of Fig. 7, with parts

broken away and shown in section through the instrument coil.

Fig. 9 is a cross sectional view of the armature and coil assembly taken substantially on line 9—9 of Fig. 10.

Fig. 10 is an enlarged elevational view of the instrument shown in Fig. 7, with parts broken away.

Fig. 11 is a view in perspective of the armature supporting bracket and armature of the instrument; and

Fig. 12 is a detailed front elevational view of the armature supporting bracket, with parts broken away, taken on line 12—12 of Fig. 11.

The instrument shown in the accompanying drawing comprises a casing 1 that has a base plate 2 which carries suitable insulated contact terminals 3 and 4 and a pair of dial supporting standards 5 that are mounted 75 thereon. An outwardly extending flange 6 of the casing serves to support a correspondingly flanged bezel 7 in which a suitable crystal 8 is mounted in conventional manner by a spring ring 9.

A dial plate 10 is mounted on the standards 5 by suitable screws 11. A core 12 of non-magnetic material is secured at one end to the dial plate and serves to support a pair of concentrically arranged energizing windings 13 85 and 14 that are wound in such direction about the core 12 as to produce concentric and coaxial electro-magnetic fields that extend in the same general direction. One terminal 15 of winding 14 is connected to terminal post 4 90 and the common terminal 16 of both windings is connected to terminal post 3. The remaining terminal 17 of winding 13 is grounded to the dial plate 10.

The armature assembly 18 that is shown 95 in enlarged perspective in Fig. 5, is mounted within the core 12 of the coil and is held in place by suitable screws 19 and 20 that engage the supporting dial 10. The armature assembly comprises a U-shaped supporting 100 member 21 of non-magnetic material that has a pair of outwardly extending ears 22 and 23 formed one on each leg thereof and apertured to receive the securing screws 19 and 20. Opposite side portions 24 and 25 of the U- 105 shaped support 21 have a pair of fixed iron vanes 26 and 27 mounted thereon that jointly act on an armature 28 of soft iron or other magnetic material that is carried on a pivot staff 29 in accordance with their respective 110

energizations. The armature is preferably of inverted U-shape, being secured at its upper end or base portion to the supporting pivot staff 29 by suitable collars 30 in accordance with conventional practice in repulsion types of electric indicating instruments. The legs of the armature 28 are disposed at materially different distances from the axis of rotation thereof in order to obtain differential repulsion effects which cause rotation of the indicator hand 31 to different indicating positions. A suitable pivot bar 32 that has an adjustable pivot bearing 33 is mounted on the armature support 21.

15 The fixed magnetic vanes 26 and 27 are respectively arranged substantially at the longitudinal center of their respective energizing windings 13 and 14.

20 A suitable control system for an instrument of the above described character is shown in Fig. 6 wherein windings 13 and 14 of the instrument are diagrammatically illustrated by the correspondingly numbered windings shown in the diagrams. A remotely 25 located impedance device 34 that is adapted to control the ratio of the currents flowing through the windings 13 and 14 by movement of a suitable contact member 35 along a resistance unit or by other appropriate 30 mechanism is energized from a source of electrical energy such for instance as a storage battery 36.

35 The windings 13 and 14 are of relatively high resistance suitable for use on either alternating or direct current, and a large number of turns in order that a strong field may be produced. Both windings are of substantially the same general resistance and magnetizing effect. The cumulative effect of the 40 windings on the armature 28 will be to energize the armature to substantially the same degree for all indicating positions of the instrument because the armature extends through both of the differentially energized 45 windings. This greatly reduces the errors of indications due to residual magnetism in the instrument.

50 The offset positions of the fixed magnetic vanes 26 and 27 and their differential magnetization by the respective windings 13 and 14 cause movement of the armature to different indicating positions because of the repulsion effects produced by differential energization of the windings.

55 The modified form of instrument shown in Fig. 7 to Fig. 12 is of a particularly inexpensive construction and embodies a damping vane that also constitutes the support for the armature.

60 The instrument here shown embodies a pressed sheet metal base 40 that is provided with a flange 41 to which suitable casings 42 may readily be secured in any conventional manner. Since the entire instrument assembly 65 is supported from the base, a great variety

of different casings may be mounted on a standard form of instrument assembly for different uses to which the instrument may be put.

65 The instrument base has a pair of suitable terminal posts 43 and 44 mounted thereon and insulated therefrom in conventional manner. The base member also has a series of suitable apertures formed therein for receiving tongues 45 formed on one end of the core 46 of the energizing windings 47 and 48. The other end of the core is secured to the dial plate 49 in any suitable manner as by welding, soldering or by flanging the end portion of the plate.

70 The solenoid windings 47 and 48 are separated by a suitable plate 50. A fixed repulsion vane 51 of iron or other magnetic material is mounted on the core 46 substantially centrally of the winding 47 and a corresponding repulsion vane 52 is similarly mounted in cooperative relation with the winding 48. The vanes 51 and 52 are preferably of soft iron and are of tapered form as shown in Fig. 8 and are mounted in opposed relation. The 85 form of circumferential extent of the repulsion vanes may be changed in order to get different deflections and scale calibrations for the instrument that are formed on a suitable dial 53 that is carried by the dial plate 49.

90 The armature assembly is separately removable from the remainder of the structure and is shown particularly in Fig. 10, Fig. 11 and Fig. 12. The supporting bracket 54 is preferably formed of brass or other non-magnetic material having a body portion of V-shaped section provided with divergent sides. The lower end of the bracket is closed by a base portion 55 that has a suitable aperture therein for supporting a pivot mounting 105 56 for one end of the armature. The upper end of the body portion has a pair of oppositely extending arms 57 by means of which the assembly is supported from the dial plate 49 of the instrument. A suitable pivot 110 bracket 58 that is secured to the arms 57 of the support by suitable screws 59 carries an adjustable pivot bearing 60 for the upper end of the pivot staff 61. The bracket 54 is cut away sufficiently to permit an indicator arm 115 62 that is carried by the pivot staff to extend over the indexed dial plate.

120 By reason of the close fit of the armature vane, that is desired, in the core for the coil which also provides a damping chamber and in order to provide a readily aligned and rigid support for the armature, the lower pivot member 56 extends through the end portion 55 of the bracket a sufficient distance to be received in a suitable aperture 63 that is 125 formed in the instrument base 41.

130 The armature comprises a bar 64 of magnetic material such as either soft or permanently magnetized iron that is carried by a suitable armature supporting vane 65. The

vane 65 may be formed of thin non-magnetic sheet metal such as aluminum alloy or from a thin sheet of bakelized fabric or other suitable light weight material. A non-metallic support and a soft iron bar are desirable if the instrument is to be used on alternating current.

One edge portion of the sheet material is suitably folded over the bar 64 to securely hold it in place and the other edge portion is folded around the pivot staff 61. A pair of metal collars 66 that tightly fit the pivot staff 61 serve to rigidly hold the armature vane in position on the pivot staff. This construction may be used with or without the particular form of indicator arm shown and in any other forms of repulsion meters.

The indicator arm particularly comprises an enlarged portion 67 through which the pivot staff extends and a pair of foldable side portions 68 that extend therebeyond and are adapted to be folded down over the upper edge of the armature vane to align the indicator vane with the armature.

The operation of this form of indicator is substantially the same as the preceding instrument except that the armature vane constitutes a damping vane that operates within the enclosed chamber of the solenoid core as will be well understood by those skilled in the art. A cover member 69 that is glued or otherwise secured to the instrument face serves to substantially close the damping chamber.

The solenoid windings are, in each case, so wound as to produce concentric, co-axial fields of the same polarity. Although a control system of the character illustrated is desired for use with either instrument, any other suitable control system could also be used without departing from the invention.

It will readily be understood that either of the instruments of the above described character will be rugged, inexpensive to manufacture, and particularly suitable for use as fuel level indicators on automotive vehicles and the like.

What I claim is:

1. An electrical indicating instrument comprising a pair of concentrically arranged magnetizing windings, a pair of fixed magnetic vanes laterally and longitudinally offset from each other relative to the axis of said windings and arranged within the windings, means operable to vary the ratio of the currents through the windings to differentially

magnetize the vanes, an armature extending well into both coils and energized in accordance with the accumulative magnetizing effect of both windings whereby said armature is moved to a multiplicity of indicating positions by the relative energization of said windings.

2. An indicating instrument comprising a pivotally mounted unrestricted armature having a portion of magnetizable material disposed substantially parallel to the axis thereof and unsymmetrical relative thereto, a pair of laterally and longitudinally offset fixed vanes of magnetic material disposed alongside the armature and at substantially the same radial distance from the rotational axis of the armature, windings for differentially energizing the respective fixed magnetic vanes to effect indicating movement of the armature to a multiplicity of indicating positions.

3. An electrical indicating instrument comprising a pivot staff, a non-magnetic vane in the form of a plate of non-magnetic material having its inner edge attached to the staff, an armature of magnetic material carried by said vane, a sector shaped damping chamber wherein said vane is adapted to operate having an arcuate wall in close proximity to the outer edge of said vane, and energizing means for controlling movements of the armature, whereby said vane constitutes a non-magnetic support for the armature and a damping device for the instrument.

4. An electrical indicating instrument comprising a pivot staff, an armature carrying vane comprising a plate having its inner edge secured to said staff, and an indicator projecting radially from said staff and having folded portions between which a portion of said vane is clamped.

5. An electrical indicating instrument comprising a pivot staff, an armature carrying vane comprising a plate having its inner edge portion encircling the pivot staff, and an indicator carried by said staff at one end of said vane, said indicator projecting radially from the staff and having folded portions between which a portion of said vane is clamped, and a securing collar on said staff at each end portion thereof between which the vane and indicator are clamped longitudinally of the staff.

In testimony whereof I affix my signature.

WILLIAM C. McCOY.
